UNITED STATES PATENT OFFICE.

EMMETT W. STULL, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTACT MEMBER.

1,260,730.

Specification of Letters Patent. Patented Mar. 26, 1918.

Application filed June 18, 1913. Serial No. 774,378.

To all whom it may concern:

Be it known that I, EMMETT W. STULL, a citizen of the United States, and a resident of Wilkinsburg, in the county of Allegheny and State of Pennsylvania, have invented a new and useful Improvement in Contact Members, of which the following is a specification.

My invention relates to contact members for electrical apparatus and has special reference to such control fingers as are employed in connection with switching devices of the rotatable drum type.

One of the objects of my invention is to simplify and improve the construction and operation of devices of the above-indicated character, and to provide an inexpensive device, the parts of which may be readily assembled and taken apart.

Another object of my invention is to provide a detachable finger which is normally maintained under a definite pressure that may be adjusted as desired, and which is provided with effective and simple means for securing good electrical connection between it and its supporting bracket.

A still further object is to provide means for securing a contact member to its supporting structure which shall embody relatively few parts that are also adapted to clamp a conductor of any size in position.

Heretofore, a controller finger of this general type has been provided with a flexible shunt that has been connected to the movable arm or finger and also to its supporting bracket or terminal block, whereby it was necessary to detach the shunt in order to remove the finger. Furthermore, prior devices have employed separate means for clamping the external conductors in position and also for securing the bracket members to a supporting structure or block.

It is my purpose to provide a controller finger of relatively few parts which are so assembled and disposed with respect to one another that the objects hereinbefore mentioned are secured and a device of special merit and utility provided.

In the drawing, Figure 1 is a view, par-

tially in section and partially in plan, of a portion of a controller embodying my invention. Fig. 2 is an end elevation of the contact member shown in Fig. 1 and Figs. 3 and 4 are sectional views, respectively, taken along the lines III—III and IV—IV of Fig. 1:

Reference may now be had to the drawing, in which the device shown comprises a rotatable drum 1, a stationary supporting block or structure 2, preferably of insulating material, a supporting bracket 3 secured thereto, a clamping member 4 adapted to cooperate therewith, a bolt 5 for securing said supporting bracket 3 and said clamping member 4 rigidly in position, a controller finger 6 which is pivotally and electrically connected to the bracket member 3, a tension device 7 and a contact tip or member 8.

The rotatable drum 1 is provided with a conducting segment 9 which is adapted to be moved under the contact tip 8 and in engagement therewith by any suitable means. It should be understood, however, that my invention is not to be limited to rotatable drum-type controllers, since although it is particularly applicable to this class of electrical apparatus, it may be embodied in switching devices of a materially different character.

The supporting bracket 3 is preferably disposed in a transverse groove 10 that is provided in the surface 11 of the supporting block 2 and is attached rigidly thereto by means of the bolt 5 which may conveniently be a carriage bolt and which projects through the block 2 for this purpose. The head 12 of the bolt 5 is seated in a suitable opening 13 to prevent turning, its other end 14 is threaded a considerable distance 90 and is provided with washers 15 and a clamping nut 16 by means of which the bracket member 3 is clamped firmly to the supporting block 2.

The supporting bracket member 3 is provided with a transverse groove or seat 21 having a finger-positioning recess 22 in the bottom thereof. A conducting member 27

has one end 28 electrically connected to the bracket member 3 and the other end formed into a socket which is fitted into the groove 21 and conforms closely to its contour. An arm 17 extends outwardly from the bracket 5 to support the finger 6 and is provided with a tongue 18 which projects through an opening 19 in the finger 6 to prevent lateral displacement of the same.

10 The finger 6 is preferably made from conducting sheet material, although, of course, it is not essential that it be so constructed, as any suitable material may be employed. The tip or contact member 8 is suitably secured to the outer end 23 of the finger and the inner end 24 is provided with a centrally located tongue 25 which projects into the recess 22 to prevent lateral displacement of the finger. A member 26 is closely fitted around the end 24 of the finger 6 and is riveted thereto, thus constituting an end portion for the finger 6 which may be seated within the socket of the member 27 and provide good electrical contact therewith.

15 In order to maintain the finger 6 under pressure, a spring 29 is secured to the outer end 23 of the finger 6. An adjusting screw 30, which has a screw-thread engagement with the projecting arm 17 of the bracket 3, is interposed between the end 24 of the finger 6 and its support 17 and serves to hold the finger 6 in yielding engagement with the socket member 21 and the support 17. By adjusting the position of the screw 30, varying degrees of pressure may be secured between the contact tip 8 and conducting segment 9 of the rotatable drum without changing the position of the finger 6 when out of engagement with the segment 9.

20 By changing the position of the screw 30 relative to the supporting socket 21 and the contact tip 8, the point of application of the tensile forces of the spring 29 is changed, and, therefore, the pressure of the member 26 within the socket 21 may be caused to bear any desired ratio to the pressure exerted by the contact tip 8 upon the segment 9. With the screw 30 in the position shown in the drawing, the pressure

25 upon the seat 21 will be substantially three times that of the contact tip 8 upon the segment 9, thus insuring good electrical connection between the finger 6 and the conductor 27. The tip 8 may, therefore, be caused to exert a considerable degree of pressure upon the segment 9 with but a small degree of movement when brought into engagement therewith. Moreover, a slight movement of the member 26 within the socket 21, which occurs when the finger 6 is raised by the engagement of the contact tip 8 with the segment 9, maintains good electrical contact between the members 26 and 27.

30 In order to detach the control finger 6, it

is merely necessary to withdraw the screw 30, since the finger rests upon the members 27 and 17. The finger 6 may therefore, be removed without releasing a flexible shunt, as was necessary with control fingers 70 heretofore employed.

One end 35 of the supporting bracket 3 is longitudinally grooved to receive the end of a conductor 36, and, co-operating therewith, is the clamping member 4 having a 75 grooved portion 37 for engaging the conductor 36. The other end 38 of the member 4 is curved inwardly to bear upon a raised portion of the conductor 27 and thus hold it in close engagement with a corresponding 80 raised portion 39 of the bracket 3. Substantially midway between the ends of the clamping member 4 is an opening 40 of liberal size and having flaring end portions through which the upper end of the bolt 5 85 extends. Nuts 42 are provided upon the upper end of the bolt 5 for tightly holding the ends of the clamping member 4 in electrical engagement with the conductors 36 and 27. It will be evident from the structure of the clamping member 4 that it may serve to clamp conductors of widely varying sizes with equally effective results.

Attention is directed to the fact that the single bolt 5 which projects through the 90 supporting block 2, the bracket member 3, and the clamping member 4 serves to separately and independently clamp the conductor 36 in position and also to secure the bracket 3 to its supporting structure 2. 100

Obviously, the structural details and arrangement and location of parts may be varied materially without departing from the spirit and scope of my invention and such modifications are intended to be covered by the appended claims.

I claim as my invention:

1. A contact member for electrical apparatus, comprising a supporting bracket having a transverse groove, a detachable finger having an end adapted to be seated in said groove, and a conducting member interposed between said bracket and said end of said finger.

2. A contact member for electrical apparatus, comprising a supporting bracket having a transverse groove, a detachable finger having an end adapted to be seated in said groove, and a plurality of conducting members interposed between said bracket and 110 said end of said finger and respectively secured thereto.

3. A contact member for electrical apparatus, comprising a supporting bracket having a transverse groove, a detachable finger 125 having an end adapted to be seated in said groove, and a plurality of conducting members one of which is disposed in said groove and mechanically and electrically associated with said bracket and the other of which fits 130

closely around said end of said finger and is mechanically and electrically associated therewith.

4. A contact member for electrical apparatus, comprising a supporting bracket having a transverse groove, a detachable finger having an end adapted to be seated in said groove, and means severally associated with said bracket and said finger and mechanically independent of each other for making a good electrical connection between said finger and said bracket.

5. An electrical contact member comprising a supporting bracket, a conducting finger resiliently associated therewith and having one end resting against said bracket, and conducting members respectively secured to said finger and to said bracket and interposed between them.

6. An electrical contact member comprising a supporting bracket, a conducting finger resiliently pressed against said bracket, and means interposed between said bracket and said finger and mechanically secured to only one of said parts for providing a good electrical connection between said parts.

7. In a contact device for electrical apparatus, the combination with a supporting member, a bracket arm having a portion to receive a conductor, and a clamping member coöperating with said bracket arm and said conductor, of a bolt and a plurality of independent means coöperating therewith for respectively securing said bracket arm to said supporting member and holding said conductor in position.

8. In a contact device for electrical apparatus, the combination with a supporting member, a bracket arm having a portion to receive a conductor, and a clamping member coöperating with said bracket arm and said conductor, of common means coöperating with said supporting member, said bracket arm and said clamping member and plural means coöperating with said common means for respectively fastening said arm to said supporting member and clamping said conductor in position.

9. In a contact device for electrical apparatus, the combination with a supporting member, a bracket arm having a portion to receive a conductor, and a clamping member coöperating with said bracket arm and said conductor, of a single member projecting through said supporting member, said bracket arm and said clamping member, and separate means coöperating with said single member for independently securing said bracket arm and said conductor in position.

10. In a contact device for electrical apparatus, the combination with a supporting member, a bracket arm having a portion to receive a conductor and a bearing portion, and a clamping member having a rounded end adapted to rest upon said bearing portion

and another end adapted to rest upon said conductor, of means coöperating therewith for holding said clamping member against said conductor.

11. In a contact device for electrical apparatus, the combination with a supporting member, and a base member having a conductor seat and a bearing portion, of an upwardly curved clamping member adapted to coöperate with said bearing portion and said conductor seat, a single member projecting through said supporting member, base member and clamping member, and means disposed between said base member and said clamping member and above said clamping member for independently clamping said parts in position.

12. In a contact device for electrical apparatus, the combination with a supporting member, and a base resting thereon and having a recessed central portion, of a threaded bolt projecting through said supporting member and said recessed central portion of said base, a nut coöperating with said bolt and disposed within said recessed portion for securing said base to said supporting member, a clamping member bridging said recessed portion and having its ends resting upon said base, said bolt projecting through said clamping member intermediate its ends, and another nut coöperating with said bolt and engaging said clamping member.

13. In a contact device for electrical apparatus, the combination with a supporting member, and a movable conducting member, of a contact finger having one end adapted to slidably engage said conducting member and the other end held in yielding engagement with said supporting member, and a conducting member interposed between said supporting member and said other end of the contact finger.

14. A contact member for electrical apparatus comprising a main body member, a finger having an end adapted to rest upon said body member, and a plurality of conducting members respectively attached to said body member and said finger and interposed between them.

15. A contact member for electrical apparatus comprising a main body member having a recess therein, a finger having an end adapted to rest in said recess, and flexible conducting members associated with said body member and said finger and disposed within said recess and interposed between them.

16. A contact member for electrical apparatus, comprising a body member having a projecting arm, a finger normally resting upon said body member and the end of said arm, a flat spring secured to said finger and disposed in substantial alignment therewith, and means coöperating with said spring and

said body member and disposed intermediate one end of said finger and the free end of said projecting arm for securing said finger in position and adjusting the force of said 5 spring.

In testimony whereof, I have hereunto

subscribed my name this 7th day of June, 1913.

EMMETT W. STULL.
